CLAIM

The ornamental design for a kitchen timer, as shown and described.

DESCRIPTION

FIG. 1 is a right elevational view of a kitchen timer showing my novel design;

FIG. 2 is a left elevational view thereof;

FIG. 3 is a front side elevational view thereof;

FIG. 4 is a rear side elevational view thereof;

FIG. 5 is a top plan view thereof;

FIG. 6 is a bottom plan view thereof; and,

FIG. 7 is a front perspective view thereof.

The broken lines are included for the purpose of illustrating portions of the kitchen timer that form no part of the claimed design.
